UNITED STATES PATENT OFFICE.

PAUL M. HOTCHKIN, OF CHICAGO, ILLINOIS.

HOSPITAL NIGHT LIGHT.

Application filed August 26, 1926. Serial No. 131,771.

My invention relates to an illuminating device and has reference to a structure more particularly adapted for use for the purpose of illuminating the floor of rooms or apartments, or places of assembly, where it is desired to retain a subdued light above the plane of the light unit and at the same time give sufficient illumination to the floor so that persons moving about may discern objects thereon. My invention has especial reference to an illuminating device that may be readily installed at the baseboard or near the floor of a hospital room, ward, or hall, or it may be placed alongside the aisles of cinema auditoriums where it is customary to maintain the auditorium in a darkened condition, but to illuminate the floor to such an extent that persons in the audience may be guided through the aisles to the exits. In hospitals it is frequently desirable to darken the room of a patient, as a result of which the nurses and attendants coming into the room from a lighted hallway cannot observe objects in the room until their eyes have become accustomed to the darkened quarters.

My present structure is conveniently made in the form of a box or housing that may be readily mounted upon the studding or similar partition during the construction of the building, prior to the application of the plaster, so that a recess is left in the wall in which a suitable lamp is mounted and the recess closed by a removable front plate or closure which may be more or less ornamental to conform with the scheme of decoration. The front plate or closure is preferably fenestrated and the lamp is so mounted that the rays of light emanating therefrom cannot pass out of the structure in an upward direction. Also the amount of light passing through the fenestra of the front plate or closure may be controlled so that the desired amount of illumination of the floor is obtained. I have also provided means for a simple adjustment of the light control devices and have shielded the adjusting means in a manner so that it may not be tampered with by unauthorized persons.

Among the objects of my invention are the provision of an illuminating device of the character above mentioned that is extremely compact in construction, is dependable in operation, is formed from a mini-

mum of parts and thereby economical to manufacture, and which is novel in the arrangement and design of the divers parts. I prefer to accomplish the objects hereof and to carry out my invention in substantially the manner hereinafter fully described and as more particularly pointed out in the claims. Reference will now be made to the accompanying drawings that form a part of this specification, in which drawings

Fig. 1 is a vertical front elevation of my improved illuminating device.

Fig. 2 is a central vertical section thereof, the socket-terminal and the shade or reflector being in full elevation.

In the drawings I have employed similar reference characters to designate the same parts wherever they appear throughout the several views, and by referring to said drawings, it will be seen the structure preferably comprises a housing or enclosure consisting of vertical side walls 5, top and bottom walls 6 and 7, respectively, and a rear or back wall 8. It will be appreciated the side and rear walls may be formed of one piece of sheet metal bent U-shape in section and mounted in a vertical plane. The top and bottom walls are provided with lateral flanges 9 and 10, respectively, around their edges that fit into and are suitably secured, by "spot" or electrical welding, to the ends of the vertical walls 5 and 8, with the flanges 9 of the top wall projecting downwardly while the flanges 10 of the bottom wall project upwardly. The width of the side walls 5 is such that the boxlike housing just described may be secured to one of the studding of a building wall or partition and be accommodated between the lathing and plaster that are on opposite sides thereof. The upper portions of the side walls 5 are provided with "knock-outs" which, when one of them is removed, provides an opening 11 through which the conductor wires may be admitted laterally into the housing.

I have provided a dividing partition 12, formed similar to the top wall with its flanges 13 secured to the adjacent portions of the vertical walls 5 and 8. This partition 12 is provided with a central aperture in which a socket terminal 14 of any well-known type may be mounted and connected with the conductor wires in the usual man-

ner. The socket 14 extends through the partition 12 as seen in Fig. 2 and its lower portion is constructed to receive a suitable shade or reflector 15 that encloses the lamp or bulb 16 shown in dotted lines. The partition 12, being horizontally disposed, divides the interior of the housing into upper and lower compartments and the upper compartment is closed by means of a rectangular plate 17 that is secured to the adjacent front flanges 9 and 13 of the top wall and the partition by means of screws 18 and 19, thus closing the upper compartment to comply with fire ordinances, but it will be understood said plate may be removed whenever it is necessary to have access to the upper compartment.

The entire front of the housing is preferably closed by a cover plate 20 of rectangular shape of slightly greater dimensions than the height and width of the housing when installed, so that the edges of the cover plate may be fitted flush against the finished plaster, in the manner shown in Fig. 2 and the cover plate is secured in position by means of the upper screw 18 that connects the plate 17 to the housing, and by the lower screw 21 that screws into the front portion of the flange 10 of the bottom plate of the housing. It will be seen that the shade or reflector 15 projects, at its front edge, beyond the plane of the front edges of the side walls 5, due to the fact that the space in which the housing is mounted is usually restricted, and, due to the fact that the reflector is formed so as to project the light rays downwardly in an oblique forward direction, the cover plate 20 is provided with an outwardly bulged portion 22 of pyramidal shape and below the horizontal plane of the lamp or bulb into which the outer corner of the reflector protrudes. The front plate or closure is provided with a fenestra in the form of a horizontally elongated, rectangular opening 23, the edges of the fenestra being formed with L-shaped flanges 24 projecting outwardly from the plate 20 to provide a seat to receive a plate of glass 25 or other suitable light transmitting material that is secured in position by means of a metal cleat 26 extended over the upper edge of the window. The light from the bulb or lamp 16 will thus be emitted from the housing only in a downward direction against the floor and cannot reach the plane of the eyes of persons adjacent the same.

In order to control the quantity of light that passes out through the window, I have provided a hood or shield that co-operates with the window and consists of spaced end plates 27 of triangular shape that are connected by a back plate 28 and a bottom plate 29, thus leaving the front portion open. The end plates 27 are pivoted adjacent their

lower forward corners upon pins 30 so that the said hood or shield may be swung upon its pivots toward and from the front closure plate 20. The pivots of the hood or shield are preferably below the plane of the lower edge of the fenestra. An elongated strip 31 having lateral inwardly-extending flanges 32 is secured to the front or closure plate 20 and the pins 30 for pivoting the hood or shield are mounted in said flanges. The upper portion of said strip provides a retainer for the lower edge of the glass plate 25.

The means for moving the hood or guard consists of a bolt 33 having a knurled head 80 with a transverse slot in its end face, which bolt is screwed into a bushing 34 mounted in an aperture in the portion of the closure plate 20 opposite or alongside the front edge of the member 29 of the hood. The bushing 85 is threaded internally so that when the bolt is rotated, its inner end will impinge against the forward edge of the hood member 29 and cause the hood to be moved so that its upper edge will approach the window. A reverse movement of the bolt permits the hood to gravitate until its inner longitudinal corner rests upon the bottom plate 7 of the housing. The external portion of the bushing 34 is also threaded and a cup-shaped guard or protector 35 is screwed thereon so as to cover the head or projecting portion of the adjusting bolt and said guard is provided with a central aperture 36 in its outer end through which a screw driver may be inserted into the slot in the head of the bolt 33 for rotating the latter. Under ordinary conditions the guard 35 may be omitted but where there is liability of unauthorized persons tampering with the same and thus changing the adjustment of the hood, the guard 35 may be employed so that the only manner of rotating the bolt 33 is by means of a screw driver or similar tool.

It is possible for other means to be employed to control the quantity of light which passes through the fenestrated front plate and other means than those disclosed may be employed for adjusting the hood. I desire it understood, therefore, that I do not limit myself to the precise construction herein disclosed and that alterations and modifications thereof are fully contemplated as coming within the scope of my invention as expressed in the appended claims.

What I claim as new is:—

1. A device of the kind described comprising a housing having a fenestrated front wall, a lamp therein above the horizontal plane of the fenestra, a pivoted hood within the housing for controlling the quantity of light passing through said fenestra, said hood pivoted to gravitate away from the fenestra, and means operable from the exterior of the housing for moving said hood upon its

5 pivot and maintaining the same in divers positions of adjustment.

10 2. A device of the kind described comprising a housing having an open front, a fenestrated wall closing the front of the housing, a lamp within the housing above the plane of the fenestra, a hood mounted upon said closure wall and controlling the quantity of light passing through said fenestra, and means mounted upon said wall 15 and operable from the exterior of the housing for moving and maintaining said hood in divers positions of adjustment.

15 3. A device of the kind described comprising a housing having an open front, a fenestrated wall closing the front of the housing, a lamp within the housing above the plane of the fenestra, a hood pivoted upon the lower portion of the closure-wall below the 20 fenestra, and a rotatable cam element mounted upon the wall and operable from the exterior for moving and maintaining said hood in divers positions of adjustment.

25 4. An illuminating device comprising a housing having an open front, a removable fenestrated wall closing the front, a lamp within said housing, a concavo-convex hood mounted upon said front wall and adapted to open and close said fenestra, said hood being pivoted so as to be constantly urged by 30 gravity away from the fenestra, and means engaged with said hood and operable from the exterior of the housing whereby to move

said hood and support the same in divers positions.

35

5 5. An illuminating device comprising a housing having an open front, a removable fenestrated wall closing the front, a lamp within said housing, a concavo-convex hood mounted upon said front wall and adapted to open and close said fenestra, said hood being pivoted so as to be constantly urged by 40 gravity away from the fenestra, and a cam device rotatably mounted on housing having a portion engaged with said hood and 45 operable from the exterior of the housing whereby to move said hood and support the same in divers positions.

6. An illuminating device comprising a housing having an open front, a fenestrated wall closing the front of the housing, a transverse partition dividing the interior of the housing into separated compartments, a lamp mounted on said partition and arranged to project light through said fenestra, a 50 shutter pivotally mounted upon said closure wall adjacent said fenestra and adapted to open and close the latter, and a rotatable cam element mounted upon said wall and operable from the exterior of the housing 55 for changing the position of said shutter with respect to the fenestra and lamp.

Signed at Chicago, in the county of Cook and State of Illinois, this 16th day of August, 1926.

PAUL M. HOTCHKIN.
